US0D1003572S

(12) United States Design Patent (10) Patent No.: US D1,003,572 S
(45) Date of Patent:  Nov. 7, 2023

(54) SWADDLING GARMENT

(71) Applicant: Baoling Han, Shandong (CN)

(72) Inventor: Baoling Han, Shandong (CN)

() Term: 15 Years

(21) Appl. No.: 29/873,340

(22) Filed: Mar. 30, 2023

(51) LOC (14) Cl. 02-01

(52) U.S. Cl.

USPC D2/719

(58) Field of Classification Search

USPC D2/719, 718, 728, 745, 746, 823, 824, D2/826, 847; D6/603, 608

CPC A41B 13/06; A41B 13/065; A41B 13/00; A41B 13/005

See application file for complete search history.

(57) CLAIM

The ornamental design for swaddling garment, as shown and described.

DESCRIPTION

FIG. 1 is a flat front elevational view of swaddling garment with the buttons open, showing my new design;

FIG. 2 is a rear elevational view thereof;

FIG. 3 is a front side perspective view of the swaddling garment in close status, showing my new design;

FIG. 4 is a left perspective view of the swaddling garment in half open status, showing my new design; and,

FIG. 5 is a right side perspective of the swaddling garment in close status, showing my new design.

1 Claim, 5 Drawing Sheets
